Patented Nov. 25, 1969

216,127

CHRISTMAS TREE ORNAMENT

Kurt S. Adler, 1107 Broadway,
Riverdale, N.Y. 10010

Filed Feb. 5, 1969, Ser. No. 15,655

Term of patent 3½ years

Int. Cl. D11—05

U.S. Cl. D29—1

Fig. 1

Fig. 2

Fig. 3

Fig. 4

FIGURE 1 is a side elevational view of a Christmas tree ornament, showing my new design;

FIGURE 2 is a top plan view thereof;

FIGURE 3 is a bottom plan view thereof; and

FIGURE 4 is a second side elevational view thereof as seen from the right hand portion of FIGURE 1.

I claim:

The ornamental design for a Christmas tree ornament, substantially as shown.
